TELEVISION TRANSMITTING SYSTEM

Ray D. Kell, Haddonfield, N. J., assignor to Radio Corporation of America, a corporation of Delaware

Application December 24, 1940, Serial No. 371,514

5 Claims. (Cl. 178—7.1)

My invention relates to television transmitters and particularly to transmitters in which the picture signals frequency modulate the carrier wave.

It has been the practice to operate amplitude-modulated television transmitters in such a way that black in the picture signals will drive the power amplifier substantially to its continuous output rating while the synchronizing pulses drive it substantially to maximum power output, this being permissible because the synchronizing pulses occur for only a small part of the total time and do not add greatly to the power that the anodes of the amplifier must dissipate. A transmitter which is operated in this way is described and claimed in my Patent 2,298,797, issued October 13, 1942, and entitled "Television transmitters."

While, for a given tube complement, the use of frequency modulation gives a certain gain in the receiver output as compared with that obtained when using amplitude modulation, there is the disadvantage that, since the carrier amplitude is constant, the power amplifier output for synchronizing pulses is the continuous rating output rather than the maximum output. This fact offsets, to a certain extent, the advantages of frequency modulation.

An object of the present invention is to provide an improved television or picture transmitter in which the advantages of frequency modulation are obtained without the disadvantage of not being able to drive the transmitter to maximum power output by the synchronizing signals.

A further object of the invention is to provide an improved method of and means for transmitting television signals or the like.

In accordance with a preferred embodiment of the invention, the carrier wave is frequency-modulated by the picture signals only, the carrier wave amplitude having the maximum amplitude permitted by the continuous power rating of the power amplifier tubes, and it is amplitude-modulated by the synchronizing pulses. By both frequency modulating and amplitude modulating the carrier wave in this manner, it is possible to realize the advantages both of frequency modulation and of the system described in my above-identified patent.

The invention will be better understood from the following description taken in connection with the accompanying drawing in which

Figure 1 is a circuit diagram of a television transmitter embodying my invention.

Figure 2 is a view illustrating the modulated carrier wave which is radiated from the transmitter, and

Figure 3 is a view showing the overall selectivity characteristic of a television receiver for receiving the signal transmitted from the transmitter of Figure 1.

5 Referring to Figure 1, there is shown a television transmitter comprising a carrier wave oscillator 10 which may be of a well-known type having a tuned circuit 11, one end of which is coupled to the grid of the oscillator tube 13 by a condenser 14.

The output of oscillator 10 is frequency-modulated by the picture signal indicated at 5 which is supplied from a pickup tube 9, amplified by a video amplifier 16 and applied through a switch 15, a blocking condenser 17 and an inductance coil 18 to the grid of a reactance tube 19. In the embodiment here described, this picture signal does not include synchronizing pulses.

20 The function of the reactance tube 19 is to vary the effective reactance across the oscillator tuned circuit 11 in accordance with the voltage amplitude variations on the grid of the reactance tube. Thus a frequency-modulated carrier wave is obtained. In the particular example shown, the tube 19 is connected across the tuned circuit 11 by a connection from the plate of tube 19 to the plate of oscillator tube 13 and by a connection from the cathode of tube 19 to ground. A resistor 21 connected between the grid and plate of tube 19 through a blocking condenser 22 functions, together with the grid-cathode capacity indicated at 23, to provide the necessary out-of-phase component for the reactance tube operation.

35 A diode 26 is provided to reinsert the direct current component of the picture signal. The D.-C. reinsertion circuit operation is well known and may be explained briefly as follows: The black level or blanking pulses are of positive polarity at the plate of diode 26 and will cause a flow of diode current whenever they drive the diode plate positive with respect to its cathode. This puts a charge on coupling condenser 17. At the end of a pulse, the condenser 17 loses a small part of its charge through a resistor 27 whereby the D.-C. voltage across condenser 17 may always have a value determined by the height of black level as measured from the A.-C. axis of the signal. It is assumed, of course, that black in the picture has been made to go to a fixed level at a preceding point in the system, after which the D.-C. component was lost.

40 The biasing battery 28 sets the voltage level at which the diode 26 passes current. Battery 28 also applies a negative bias to the control grid of

tube 19 so that the synchronizing pulses never drive the grid of tube 19 positive with respect to its cathode.

The inductance coil 18 is provided to separate the electrode capacities of tubes 19 and 26 in order to hold up the high video frequency response and, also, in order to keep the oscillator 10 from feeding back radio frequency energy into the video circuits.

The frequency-modulated output of oscillator 10 is amplified by a power amplifier 31 and radiated from an antenna 32.

The system described so far produces a carrier wave which is not modulated by synchronizing pulses. It is modulated only by picture signal and is of a constant amplitude which drives the power amplifier substantially to its maximum output as fixed by its power rating for continuous output.

In accordance with my invention, the synchronizing pulses, which are produced by a suitable synchronizing pulse generator 30, are put on the carrier wave by amplitude modulation. This may be accomplished by supplying the synchronizing pulses (for both line synchronizing and framing) to an amplifier or modulating tube 36 which is coupled to the grid circuit of the power amplifier 31 for grid modulation. This coupling, in the example illustrated, is through a coupling condenser 37 and a switch 38.

When grid modulation is employed, the amplifier 31 preferably is biased by means of a suitable voltage source 39 for class B operation. A coil 41 provides the necessary impedance between ground and the point at which the modulating voltage is applied.

As indicated at 42, the synchronizing pulses are applied to the modulator 36 with such polarity that they drive the control grids of the tubes in power amplifier 31 more positive so as to momentarily increase their power output.

The modulated wave which is radiated from the transmitter is shown in Figure 2. It will be seen that up to a certain amplitude the carrier wave is frequency-modulated, this amplitude representing black in the picture in the example shown, and that, beyond this amplitude, the carrier wave is amplitude-modulated. In Figure 2, the amplitude-modulated portion of the wave indicated at 42A has been produced by the horizontal or line synchronizing pulses.

It should be understood that the amplitude modulation may be obtained by other methods than grid modulation. For example, by connecting the switch 38 to the conductor 46, the power amplifier 31 may be plate-modulated, as taught by Heising. For plate modulation, the switch 47 is opened whereby the choke coil 48 is effectively connected into the amplifier plate circuit. When plate modulation is employed, the amplifier 31 may be operated class C, to obtain maximum efficiency and maximum power output.

It will be understood that the synchronizing pulses and the picture signal occur in a fixed time relation with respect to each other in the usual manner, as taught by the prior art, the line synchronizing pulses occurring at the end of each scanning line and the framing pulses occurring at the end of each field or frame deflection.

Television receivers preferably are operated to give single side band reception as described in Grundmann Patent 2,261,803, issued November 4, 1941, and entitled "Wide band amplifiers." Such receivers have the frequency response char-

acteristic shown in Figure 3. When receiving a carrier wave modulated according to the present invention, the receiver is tuned so that the carrier frequency f_0 is located half way down on the slope of the low frequency side of the characteristic curve, as indicated. The picture signals have been made to deviate or swing the carrier wave over the entire slope of the curve between the frequencies f_1 and f_2 . It may be noted that, when the receiver selectivity curve is drawn for the I. F. amplifier with the response plotted against the I. F. signal itself, the curve is reversed with the carrier on the high side because the local oscillator frequency is so located with respect to the incoming signal as to invert the frequency.

It is during the time the signal is deviated to the frequency f_2 representing black in the picture that the amplitude of the carrier wave is increased by a synchronizing pulse. Thus, there appears on the second detector of the receiver a signal that is of greater amplitude than any resulting from frequency deviation.

If desired, the synchronizing pulses may be made to both frequency-modulate and amplitude-modulate the carrier wave. For example, a mixture of picture signal and synchronizing pulses may be supplied by an amplifier tube 51, and supplied through the switch 15 to the rectance tube 19. At the same time, the synchronizing pulses are being supplied to the amplitude modulator tube 36 whereby the output of oscillator 10 is amplitude-modulated as well as frequency-modulated by the synchronizing pulses.

In the embodiment of the invention just described, the oscillator output preferably is deviated between frequencies f_1 and f_2 (Fig. 3). In this case, frequency f_2 represents a certain amplitude of synchronizing pulse. The desired additional amplitude of the synchronizing pulse is obtained by the amplitude modulation.

I claim as my invention:

1. The method of operating a television transmitter having a power amplifier for amplifying a modulated carrier wave which comprises frequency-modulating said carrier wave with said wave at an amplitude which drives said amplifier substantially to its maximum continuous power output rating and amplitude-modulating said carrier wave by periodically recurring synchronizing pulses.

2. The method of operating a television transmitter having an amplifier for amplifying a modulated carrier wave which comprises frequency-modulating said carrier wave with said wave at an amplitude which drives said amplifier substantially to its maximum continuous power output rating and amplitude-modulating said carrier wave by periodically recurring synchronizing pulses which periodically drive said amplifier substantially beyond said continuous power output rating.

3. The method of television transmission in a system wherein at the receiver the frequency response curve of a frequency discriminator has a slope extending between certain frequency limits located substantially at the ends of said slope which comprises frequency-modulating a carrier wave by picture signals with the frequency deviation having substantially the said frequency limits, and amplitude-modulating said carrier wave periodically by synchronizing pulses during the time it is deviated to one of said frequency limits representing black in the picture.

4. The method of operating a television trans-

mitter having a power amplifier for amplifying a modulated carrier wave which comprises frequency modulating a carrier wave with picture signals and with periodically recurring synchronizing pulses at an amplitude which drives said amplifier substantially to its maximum continuous power output, the said modulation by the pulses producing a deviation to a frequency representing black in the picture, and simultaneously amplitude modulating said carrier wave by said synchronizing pulses.

5. A television transmitter comprising means

for producing a carrier wave which is to be modulated by picture signals and periodically recurring synchronizing pulses, means for frequency modulating said carrier wave by said picture signals and for producing a deviation to a frequency representing a predetermined level such as black in the picture during the occurrence of said pulses, and means for amplitude modulating said carrier wave simultaneously by said synchronizing pulses.
